UNITED STATES PATENT OFFICE.

EDWIN L. BOSWORTH, OF CAMBRIDGE, MASSACHUSETTS.

CARD INDEX.

Application filed November 7, 1921. Serial No. 513,404.

This invention relates to a card index system. The principal objects of the invention are to provide an index of such a nature as to be capable of general application for the purposes for which card indexes are used ordinarily, as well as for dictionaries, directories, and lists of various kinds, either letters, words, numbers, or other characters; to provide a system of this kind of such a character that it will not be limited in any way to a comparatively small number of subjects, or be unwieldy or present any difficulty when an extremely large number of words or numbers are listed under it; to provide means whereby, under any circumstances, the particular word, number or the like, which it is desired to find can be located with great facility and ease, and that necessitates no complicated instructions or any great experience in the use of the system; to provide a system of this character wherein there will be a number or series of divisions, subdivisions, and in fact, in which, if desired, the subdivisions can be subdivided to any desired extent so that anyone using the index can find the word or number he is after very readily by selecting a card which represents the first letter or numeral and then selecting the card behind that which represents the second one, and the card behind that which represents the third, and so on, the divisions being carried out to any desired degree in accordance with the particular subject matter that is being indexed.

The invention also involves the provision of division cards having certain characteristics facilitating their use for the above specified purposes, and also adapted to have printed or written upon them the subject matter contained in the matter indexed, that is, in the dictionary or the like for which it is used. The cards also have certain relationships to each other, as will appear, for the purpose of coordinating them in a suitable way to accomplish the above mentioned objects.

Another feature of the invention consists in the provision of a booklet which is composed of a number of pages, each in a general way representing a card, and suitable for use in certain cases where there is a large amount of matter to be subdivided, and constituting a more convenient way of handling it.

Other objects and advantages of the invention will appear hereinafter. 55

Reference is to be had in the accompanying drawings in which:

Fig. 1 is a perspective view of a small part of a card index constructed in accordance with this invention and shown as being used 60 as a dictionary.

Fig. 2 is a front view of the first division card of that index.

Fig. 3 is a similar view of a card which constitutes a second division card in one of 65 the series.

Figs. 4 and 5 are respectively third and fourth division cards all adapted to be located in the proper places behind the card in Fig. 2. 70

Fig. 6 is a perspective view of a booklet which constitutes a substitute for several cards.

Fig. 7 is a view similar to Fig. 4 showing a third division card modified so as to be 75 used for a city directory.

Fig. 8 is a modified directory card; and

Fig. 9 is a view similar to Fig. 5 showing a fourth division card modified so as to be used for indexing numerical matter. 80

As stated above, this card index system is suitable for use for many purposes. In the first five figures, I have shown it for use for a dictionary. Referring now to these figures in detail, the whole subject matter of the dictionary is first divided in the natural way and in the way which is common in card indexes, into twenty-six divisions, each division representing one letter of the alphabet. If the index were used for numbers it would be divided into ten divisions, each representing a digit, or in multiples of ten. 85

These divisions are made by the use of the required number of primary division cards 10 each with a tab 11 thereon having a letter, number designation or character 12 representing the initial letters of the various words. This card, however, is preferably made with an extension 13 on the tab 11 at a lower level than the tab and having additional data. In the form shown in Figs. 1 and 2 this extension 13 is shown as containing the letters a-z. This means that behind the particular card 10 shown there are subdivisions representing the second letter of 95 the word from a to z inclusive. The same 100

principle is followed out preferably throughout the whole index. If it is desired to divide the subject matter behind this card in two divisions two such cards would be used, 5 one having at this point the letters a-m, for example, and the other n-z. As clearly indicated in Fig. 2 this constitutes the whole of the printing or lettering on the division card 10, preferably, and each of the others is made 10 up in the same way. If, however, there is only subject matter under any initial letter to occupy one card, it can be placed directly 15 on the division card as indicated hereinafter. I refer to these cards through this specification 20 as No. 1 division cards. The tabs 11 are arranged in staggered relationship to facilitate the use of the index.

In Fig. 3 I have shown what I call a No. 2 division card 20. This card is not, usually, 25 substantially a blank like the cards 10, but is provided with certain marks, letters, and words as will appear. In the first place, it is provided with a tab 21 having a designation or character 22 thereon, in this case the 30 letter n. Furthermore it is provided with an extension 23 to that tab. On this extension, at a lower level, there is a letter, designation, or character 24 in this case "o-t". It will be observed that this is made up of 35 two letters in this case. This will occur frequently in this index.

Now this second card shown is designed to be used behind the first No. 1 card having the letter A on the tab 11 thereof. In other 40 words, it relates to words in the dictionary which commence with the letter A. The character 22 on this card represents the second letter of each word on the card or on any further divisional or other cards behind it. For the purpose of having all the data necessary 45 on the card itself, the letters A and n are shown at the left-hand upper corner of the card, but on the body of it below the level of the tab and in the position designated 50 25. Now this card also, besides indicating the second letter of the word, also may contain lettering as shown indicating the third letter. This third letter o or t is indicated by the character 24, and by the third 55 letter or lettering at the point 25. All the words on this card commence with the letters a n and have as their third letters those from o to t. This fact is indicated by these three letters a n o at the point 25, and is also indicated by the letter A on the corresponding 60 No. 1 division card, and the letters n and o-t at the points 22 and 24 on this card itself.

In the form illustrated here, I have shown a 65 number of words printed on the card and it will be understood that their definitions are intended to appear there if this is being used for a dictionary. They are arranged alphabetically in the usual way and the first one is the first word under the general heading A n o, in this case the word anoa. It can be

considered that the letters a n o at the point 25 at the left head three columns which are blank below them part or all the way down the card. Just at the right of them there is a fourth column represented by the numeral 70 26. The first letter at the top of this column but below the row of letters A n o is the letter a. This indicates, of course, that the first word begins with the letters A n o a. Each of the letters in the column 26 may head a 75 blank space to indicate that all the words following that space to the right have for the fourth letter the one located in the column 26 above it. For example the letter d, the fourth letter down in the fourth column is 80 written in the place indicated and the next six spaces are left blank below which indicates that those next words below that level have as their first four letters the letters a n o d. Now, if it is desired to divide these 85 up further, a fifth column 27 can be used as indicated which is shown as made up of the fifth letters of the words, a, e, i, o, y. These indicate the fifth letter of the words opposite as will be seen clearly from the few words 90 that are selected and printed out on the drawings. On this card, all the words shown beginning with ano after anoa are included and I continue with these following which begin with ans and ant. Now, in order to 95 represent at the top of the card 20, the facts that have been indicated above, I provide some characters, letters, or numerals 28 to show how far this card goes in including the fourth letter of the words. In this case the 100 fourth letter under the last third letter, t, goes from a-h inclusive, and so the designation 29 in the form of an &, indicates that more words are to follow on the next card under the heading A n t. This is placed before the characters at 28 to show that something is to follow. It will be seen, therefore that on the card next behind the card represented in Fig. 3 there will be characters 22, 24, 25 just as there are on this card, but at 105 the point 28 will be the letters h-z provided the next card contains all the rest of the words beginning with A n t. If not, the & (29) will appear after this character at 28 on the No. 2 card to show that the words 110 commencing with Ant are not all on the card, and to show in which direction to go to find the others.

This description has presumed that all the words commencing with Ano, ans, and ant can be contained on two cards. It is obvious, however, they can be divided up into any other desired number of cards, and that the cards between the first and last will have the designation 29 at both ends of the character 115 or sign at 28 as in Fig. 5. This description would do for an abridged or pocket dictionary in the main, but there are some cases even in a small dictionary where even further divisions are necessary.

In Fig. 4 I have shown a card 30 which I call No. 3 card. This is to be used to show the third letter at 32 on the tab 31. When such a card as this is employed, the corresponding No. 2 card 20 has the character 22 on it and a designation at 24 to show what is on the No. 3 card behind it, but the words of the dictionary containing these letters are on the No. 3 cards 30. In this case, I have shown it as having a No. 1 card representing the letter A similar to Fig. 2, and a No. 2 card representing the letter n. In other words, the designation at 35 on the No. 3 card is A n t i n, the fourth letter being the same as the character at 34 on the extension 33 of the tab. Now, on this card, the fourth letter i appears on the card and so I have a fourth column that might indicate any other letters which might follow under it. I have shown also a fifth column 37, the purpose of which will be obvious from what has been stated above. This No. 3 card has at the top a tab 31 similar to tab 21 of the card of the second order but bearing the third letter of the words, t indicated by 32, and having an extension 33 with the fourth letter i, indicated by 34, on it. Just below the tab on the card is an & followed, in the particular third card illustrated, by the inscription n-z preceded by a "diæresis" 129. The & has a meaning analogous to that explained above, that is, it indicates that the letters a-n accompanying it are of the next place following that of the index letter 34, at the right of the tab, or are fifth letters of words on the card. Since these letters do not start at the beginning of the alphabet the diæresis is inserted before them to indicate that there are words beginning with Anti and having fifth letters preceding n, on another card of the third order before this one. The designation 35 on this card might be only Anti, omitting the fifth letter.

In Fig. 5, I have shown a No. 4 card 40, and I have designated the parts 41, 42, 45, 46, 47 to correspond with the designations 31-37, and also 21-27 respectively. In other words, these numerals represent, not the same letters or numerals, but those having the same relations to the words on the card that the corresponding ones do in Figs. 3 and 4. The designations on this card show that the card before it contained at the end words beginning in A n t i c. The diæresis and & signs on card 40 as well as on card 30 show that this is a continuation from the card before this having the designation "Anti". It is to be understood that in many cases no No. 4 cards will be used, and in fact this is true of all the others except the No. 1 card. If in the case of an abridged or pocket dictionary, all the words commencing with X can be placed on the No. 1 card having the letter X at the top at the point 12, there need be no No. 2 cards or any other cards behind it in that division. The staggering of the

tabs 11, 21, 31, 41, etc. is carried out throughout the index. The tabs of different orders can be distinguished from each other if desired by differences in color, shape, or size.

In using this system for an unabridged 70 dictionary, I find that so many cards are used that it will be more convenient to connect some of them permanently so as to form a booklet of a number of cards or leaves, and I have shown this in Fig. 6 in which the booklet 75 60 is intended to contain all the words commencing with the three letters c o m. In this case designations can be placed on the outside corresponding with those on card No. 3 for example. 80

Inside the booklet there are a plurality of leaves divided into groups. The front leaf of each group has at the top a tab 61 having a letter or other character 62. In this case there may be as many as twenty-six leaves. 85 On the first leaf, for example, would be words commencing with "coma" or parts thereof. Behind each of the leaves having the tab 61 are pages or leaves further dividing up the words, and although I have not 90 shown them separately certain ones are provided with tabs as 63 at the right having a letter or other designation as 64 representing the fifth letter of the word. These subdivisions can be made or not according to how 95 many words there are under each letter 62. The several leaves can be further marked on the front as in Figs. 3, 4, 5 if desired. It is to be understood in this connection that it is not at all essential that the characters 65 100 be three in number as these booklets can be used at any point in the index. In the present instance, I have shown the booklet as taking the place of a No. 3 card, but it could take the place of a No. 2 or No. 4 card or 105 any other in accordance with this invention.

In Fig. 7 I have shown a division card designed to be used for a directory, catalogue, file or other list. This is a No. 3 card that is illustrated, and it indicates that the first 110 four letters of the last names of the parties listed in the directory are Mora. These cards like the others shown can contain any printed matter desired after the names. On this card I have shown a modification of the tab 71, 115 illustrating it in the form of a sheet metal or celluloid clip stamped out to provide tongues adapted to hold the clip in position. The extension 73 on the tab is modified also as it extends from the end of the tab opposite to that shown in Fig. 3. It is sometimes desirable to extend the index still further, and for that purpose I have shown in Fig. 8 a No. 5 card 50 having a tab 51, a character 52 on it, and an extension 53 together with the character 55, etc. This card is devoted to a single name or names, as for example the surname Johnson. The characters 52 then will not represent the fifth letter in this name but will represent the initials or given names. This by 125 130

no means exhausts the limits of this system in that respect as any desired number of division cards can be employed. It will be noted, of course, that a large number will be employed in certain places, for example where the first three or four letters constitute a common initial syllable like com. The subdivisions can be handled without as many division cards in many cases. It is to be noted 10 in this case also that a slight modification is shown, as the tab extension extends from the opposite end of the tab to that shown in Figs. 2 and 3 which may be more convenient in some cases.

15 In Fig. 9 I have shown a No. 4 card of an index of numbers, as for example patent numbers. It is thought that in view of the above description this figure will be self-explanatory.

20 It will be seen, therefore, that the invention is capable of wide use for indexing purposes, and is not restricted to the particular illustrations made herein. It is also obvious that it is perfectly flexible, and can be employed efficiently no matter how irregular 25 the work may be to which it is applied. Each card is provided with data to show just where it belongs if it is taken out for use, and they always indicate, by the data upon them, if a 30 card has been left out.

The use of the device is very simple, a word is found in it in the same way as in any dictionary, except that the divisions of the words are displayed in a convenient place so that 35 the user can more readily and rapidly select the positions in the index in which he will find the word or number for which he is looking. Much time is saved in searching for a word or number by the use of this index.

40 Although I have illustrated and described only a few forms of the invention, I am aware of the fact that other modifications can be made therein by any person skilled in the art without departing from the scope of the invention as expressed in the claims.

45 Therefore, I do not wish to be limited to any or all of the forms and details illustrated and described, but what I do claim is:—

1. In a card index, the combination with a 50 set of primary division cards, each designated to represent a series of cards, of a series of secondary division cards located between two of the first named division cards and designated to represent a series of cards constituting a sub-division, having thereon indicia showing in what division and sub-division they belong and having a column of the matter to be indexed on each of said cards having as its first character said designation of its 55 primary division card and as its second character the designation of its secondary division card.

2. In a card index, the combination with a 60 set of primary division cards, each having a prominently displayed designation repre-

senting and indexing a division or series of cards, of a series of secondary division cards located between two of the first-named division cards, and each having a prominently displayed character representing and indexing a sub-division of cards, and cards constituting said sub-divisions having thereon indicia showing in what division and sub-division they belong and having a column of the matter to be indexed having as its first character said displayed character on its primary division card and as its second character the displayed character on its secondary division card, the secondary division card having a character prominently displayed showing the third character of the first line of said matter on the sub-division cards. 70

3. In a card index, the combination with a set of primary division cards, each having a designation of a series of secondary division cards located between two of the first named division cards, and each having a designation, and cards located behind each of said secondary division cards and each having thereon a column of the matter to be indexed, that on each of said cards having as its first character said designation of its primary division card and as its second character the designation of its secondary division card, and additional series of division cards each having lines of indexed matter thereon and designated prominently with a character indicating the character in the first line of matter thereon which corresponds, in its numerical position from the beginning of the line, with the number of times the indexed matter is subdivided by all the division cards preceding and including itself. 90

4. In a card index, the combination with a plurality of primary division cards, each 105 designated with a letter of the alphabet prominently displayed thereon, of a plurality of series of secondary division cards, each series being located between two of the primary cards, and each one having a letter of the alphabet thereon and bearing words thereon alphabetically arranged and all commencing with the letter with which one of the adjacent primary division cards is designated, the individual cards of each series being designated by letters alphabetically arranged and having thereon words of which the second letter is the same as their own designating letters. 115

5. In a card index, the combination with 120 a plurality of primary division cards, each designated with a letter of the alphabet prominently displayed thereon, of a plurality of series of secondary division cards, each series being located between two of the primary cards, and each one having a letter of the alphabet thereon prominently displayed, and a number of cards between each two secondary division cards, each having data thereon arranged in lines, the first letter of 125

each line being that by which the adjacent primary division card is designated and the second letter of each line is that by which the adjacent secondary division card is designated, the last-named cards of each series being designated by letters alphabetically arranged and constituting the third letter of the first line of said data.

6. In a card index, the combination with 10 primary division cards having tabs thereon arranged in staggered relation and each having a character thereon, of a number of series of secondary division cards, said number being equal to the number of primary division 15 cards, each series being located between two adjacent primary division cards, each card thereof having a tab thereon provided with a secondary character similar to the characters on the primary division cards and arranged in the same order and in staggered relation, the several like characters on the tabs of the various series of secondary division cards being arranged in parallel rows, the secondary division cards each having thereon indexed reading matter all having as its first 25 two characters the two characters on the tab of the related primary division card and its own tab.

7. In a card index, the combination with a 30 number of primary division cards having tabs projecting therefrom and arranged in staggered relation and each having a character on its tab to indicate the first character of all the indexed matter behind that card and 35 in front of the next similar one in the index, of series of secondary division cards located between two adjacent division cards, each secondary card having a tab thereon provided with a character, and cards behind each secondary division card having thereon indexed reading matter all having as its first 40

two characters the two characters on the tabs of the front adjacent primary and secondary division cards.

8. As an article of manufacture, a division 45 card for a card index having a tab projecting therefrom and designated by a character, and an extension on the tab of less height having a character thereon, the first-named character representing the first character of 50 the matter to be indexed just behind said card and the character on the extension representing the second character thereof.

9. As an article of manufacture, a division 55 card for a card index having a tab projecting therefrom and designated by a character, and an extension on the tab of less height having a character thereon, the first-named character representing the second character of the matter to be indexed just behind said card or on it and the character on the extension representing the third character thereof, and having said two characters repeated in the order named on the card at a lower level than the tab and a third character to their left 60 representing the first character of the indexed matter.

10. As an article of manufacture, a division 70 card for a card index having a tab designated by a character and an extension on the tab of less height having a character thereon, the card having a third prominently displayed character thereon at a lower level near the extension, said card having a column of matter thereon, three adjacent characters of each 75 line of which for a distance from the top are the same, and in the same order, as the three characters on the card.

In testimony whereof I have hereunto affixed my signature.

EDWIN L. BOSWORTH.
